LAPPING MACHINE

Herbert S. Indge, Westboro, Mass., assignor to
Norton Company, Worcester, Mass., a corpora-
tion of Massachusetts

Application June 25, 1949, Serial No. 101,422

2 Claims. (Cl. 51—161)

1.

This invention relates to lapping machines and more particularly to a machine adapted for lapping cylindrical type workpieces.

One object of the invention is to provide a simple and thoroughly practical lapping machine. Another object of the invention is to provide a lapping machine in which the workpieces to be lapped are rotated and reciprocated between two opposed lapping elements. Another object of the invention is to provide a lapping machine having two opposed lapping elements one of which is rotatable and one of which is provided with a plurality of V-shaped grooves simultaneously to support a plurality of workpieces for a lapping operation. Another object of the invention is to provide such a machine with a driving mechanism for rotating at least one of said wheels and to provide means for simultaneously and axially reciprocating a plurality of workpieces during a lapping operation. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of various possible embodiments of the mechanical features of this invention,

Fig. 1 is a vertical section through the improved lapping machine;

Fig. 2 is a fragmentary perspective view, on an enlarged scale, of the opposed lapping elements, the work-pieces and the reciprocating mechanism therefor, showing the V-grooves for supporting the work-pieces arranged in radial positions.

Fig. 3 is a fragmentary plan view, on an enlarged scale, of the lower lapping wheel or work support, showing the V-grooves arranged in non-radial positions; and

Fig. 4 is a plan view, on an enlarged scale, showing the adjustment for the work reciprocation; and

Fig. 5 is an elevation of the parts shown in Fig. 4.

The improved lapping machine as illustrated in the drawings comprises a base 10 which serves as a support for an upper lapping wheel 11 and a lower lapping wheel or work supporting wheel 12. The base 10 serves as a support for a vertically extending column 13 which supports a horizontally arranged arm 14. The upper end of the column 13 is provided with a reduced cylindrical portion 15 on which the arm 14 is pivotally mounted. A shouldered surface 16 on the column

2.

13 serves to position the arm 14. A manually operable clamp 17 is provided on the arm 14 which is actuated by a manually operable lever 18 to clamp the arm 14 either in an operative position or to facilitate releasing said arm so that the arm and the upper lapping wheel 11 supported thereby may be swung to an inoperative position.

The arm 14 is provided with a vertically extending cylindrical aperture 19 which supports a vertically movable spindle 20. A rotatable pinion 21 carried by the arm 14 meshes with a rack bar 22 formed on the peripheral surface of the spindle 20. A manually operable lever 23 is provided for actuating the pinion 21 to facilitate raising or lowering the spindle 20 as desired. A pivotally mounted detent or latch 24 is fixedly mounted on a rock shaft 25 which is journaled in suitable bearings not shown and the arm 14 serves when in an operative position to engage teeth of the bar 22 to hold the spindle 20 against downward movement. A manually operable lever 26 is fixedly mounted on the rock shaft 25 to facilitate actuation of the detent or latch 24. A spider 30 is mounted on the lower end of the spindle 20. The spider 30 is fixedly mounted to the upper lapping wheel 11. A latch 31 pivotally mounted on the spider 30 serves to engage notches in a collar 32 mounted on the spindle 20, normally to hold the spider 30 and the upper lapping wheel 11 against rotation. It will be readily apparent from the foregoing disclosure that by actuation of the lever 23, the spindle 20 together with the spider 30 and the upper lapping wheel 11 may be manually raised or lowered as desired. The detent 24 may be utilized to lock the upper lapping wheel in an uppermost or inoperative position to facilitate a work loading operation. When it is desired to start a lapping operation the manually operable lever 26 may be actuated to move the detent 24 out of engagement with the rack bar 22 after which the lever 23 may be moved in a counterclockwise direction to cause a downward movement of the spindle 20 and the upper lapping wheel 11. The weight of the spindle 20, the spider 30 and the upper lapping wheel 11 are sufficient to maintain the desired lapping pressure of the upper lapping wheel on the workpieces under the influence of gravity. The upper lapping wheel 11 may if desired be a metal lap, in each case a loose abrasive lapping compound must be used. In the preferred form the upper lapping wheel 11 is a bonded abrasive wheel such as for example abrasive grains bonded by a vitrified, rubber or metallic bond.

55. The lower lapping wheel 12 is fixedly mounted

on the upper surface of a spider 35 which is keyed on the upper end of a rotatable sleeve 36. The sleeve 36 is journaled in a pair of spaced anti-friction bearings 37 and 38 which are carried by a housing or frame 39 which is in turn fixedly mounted relative to the base 10.

The lower lapping wheel 12 is provided with a suitable driving mechanism comprising an electric motor 40 which is mounted on a pivotally mounted motor support 41 supported on a rock shaft 42 within the base 10 of the machine. The motor 40 is provided with a motor shaft 43 which is provided with a V-groove pulley 44 which is connected by V-belts 45 with a V-groove pulley 46 mounted on a rotatable shaft 47. A worm 48 is formed integral with the shaft 47 and meshes with a worm gear 49 which is keyed on the lower end of the sleeve 36. It will be readily apparent from the foregoing disclosure that when the motor 40 is started, a rotary motion will be imparted through the driving mechanism above described to rotate the sleeve 36, the spider 35 and the lower lapping wheel 12.

The lower lapping wheel 12 serves as a work supporting and rotating member and may consist of either a cast iron lap or if preferred a relatively hard fine bonded abrasive wheel. The lower lapping wheel 12 is provided with a plurality of V-shaped grooves 50 which may be arranged either radially as shown in Fig. 2 or may be arranged at a slight angle to a radius as shown in Fig. 3. Each of the V-shaped grooves 50 is provided with a clearance groove 51 formed at the base of the V-groove to provide the necessary clearance for loose particles of abrasive material and metal. To facilitate the lapping action of the wheels upon a plurality of workpieces 52 to be simultaneously lapped, the upper lapping wheel 11 and the lower lapping wheel 12 are preferably formed as annuli having opposed plane operative surfaces. The width of the annuli, that is the radial distance between the outer and inner peripheral surface thereof is preferably substantially equal to the length of the workpiece to be lapped. When a plurality of cylindrical workpieces 52 have been loaded into the V-grooves 50, the upper lapping wheel 11 may then be lowered into operative engagement with the upper surfaces of the workpieces 52. In this position of the parts, when the motor 40 is set in motion to rotate the lower lapping wheel 12, the workpieces 52 being carried by the V-shaped grooves 50 and maintained in operative engagement with the operative surface of the upper lapping wheel 11 will be positively rotated by the combined action of the rotating lower lap, the V-grooves 50 and the stationary upper lapping wheel 11. By providing V-shaped grooves for supporting the workpieces during a lapping operation, out-of-round condition of the workpieces may be corrected by the lapping operation to produce true cylindrical surfaces on the finished lapped workpieces 52.

In order to facilitate the lapping operation, it is desirable to not only cause a rotary motion of the workpieces 52 between the lapping elements 11 and 12, but also to impart a simultaneous axial reciprocatory movement to the workpieces during the lapping operation. By the provision of such a reciprocatory motion, a breakup action is provided between the lapping elements and the work and the operative faces of the lapping elements are thereby caused to wear uniformly during a continued lapping operation. This reciprocating mechanism may comprise an inside work retainer 55 which has an outer peripheral sur-

face arranged to simultaneously limit the inward movement of the workpieces 52. The inside work retainer 55 is rotatably mounted on a crankpin or stud 56 which is adjustably mounted on a rotatable crank plate 57. The crank plate 57 is fixedly mounted on the upper end of a rotatable shaft 58. The shaft 58 is connected by means of a coupling 59 with a vertically arranged drive shaft 60 contained within the sleeve 36. A V-belt 61 connects the pulley 46 with a V-groove pulley 62 which is mounted on a rotatable shaft 63. The shaft 63 is provided with an integral worm 64 which meshes with a worm gear 65 keyed on the lower end of the shaft 60. An outer work retaining ring 66 rests upon the upper plane surface of the spider 35 and is provided with an upwardly extending rim 67 having an internal cylindrical surface 68 which is arranged simultaneously to limit outward motion of the workpieces 52. The outer work retainer 66 is free to float or slide on the upper surface of the spider 35 when moved by the outer ends of the workpieces 52.

It will be readily apparent from the foregoing disclosure that rotation of the shaft 60 as caused by the motor 40 and the driving mechanism above described will cause a revolving motion of the crankpin 56 to impart a gyrating movement to the inside work retainer 55. As the work retainer 55 gyrates its outer peripheral surface engaging the inner ends of the workpieces will impart a reciprocatory movement to the workpieces 52 relative to the lapping elements 11 and 12. During this reciprocatory movement, the outer retaining ring 66 slides on the upper plane surface of the spider 35 and holds the workpieces 52 in a definite relationship with the outer peripheral surface of the inside work retainer 55.

The crankpin 56 is preferably adjustably mounted on the crank plate 57 as shown in Figs. 4 and 5 to facilitate varying the extent of gyration of the inner retainer or drive plate 55 so as to vary the length of the reciprocatory stroke imparted to the workpieces 52 relative to the annuli 11 and 12. The crankpin 56 is fixedly mounted on a triangularly shaped plate 70 (Fig. 4) which is pivotally supported by a stud 71 on the crank plate 57. The plate 70 is provided with an arcuate-shaped elongated slot 72. A clamping screw 73 passes through the slot 72 and is screw threaded into the crank plate 57. The eccentricity of the crankpin 56 may be varied by loosening the clamping screw 73 and then swinging the plate 70 to position the crankpin 56, as desired, after which the clamping screw 73 may be tightened to lock the plate 70 in adjusted position. As shown in Fig. 4, the crankpin 56 is positioned for maximum throw. The plate 70 may be adjusted so that the crankpin 56 is positioned in any position desired between the full line position shown in Fig. 4 and the dotted line position 56a. In the latter position, the axis of the crankpin coincides with the axis of rotation of the crank plate 57, in which position no reciprocatory motion is imparted to the workpieces 52.

The operation of this improved lapping machine will be readily apparent from the foregoing disclosure. Assuming the upper lapping wheel 11 to be in an inoperative or raised position as indicated in Fig. 1, a plurality of workpieces 52 are mounted in the V-grooves 50, after which the detent 24 may be withdrawn by actuation of the lever 26 and the lever 23 moved in a counterclockwise direction to allow the upper

lapping wheel 11 to move under the influence of gravity into simultaneous engagement with the upper surface of the workpieces 52. The motor 40 may then be started to impart a rotary motion to the lower lapping wheel 12 and at the same time to start a gyrating movement of the inside work retainer 55. The rotary motion of the lower lapping wheel 12 and the gyrating motion of the work retainer 55 will cause a combined rotating and reciprocating movement of the workpieces 52 relative to the operative faces of the lapping wheels 11 and 12 to produce the desired lapped surface on the periphery of the workpieces.

It will thus be seen that there has been provided by this invention apparatus in which the various objects hereinabove set forth together with many thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a lapping machine having a base, a vertically movable upper lapping annulus having a plane operative face thereon, a vertical spindle slidably supported relative to said base to support said annulus, a lower work supporting annulus having an upper plane face rotatably supported on said base in axial alignment with the upper annulus, a plurality of radial V-shaped work supporting grooves extending across the upper plane surface of the lower annulus simultaneously to support a plurality of work pieces to be lapped, means including a manually operable lever-actuated gear and rack operatively connected to move said spindle for moving the upper annulus toward and from the lower annulus to position the lapping annuli in lapping engagement with the work pieces to be lapped, means including a motor on said base operatively connected to rotate at least one of said annuli, the rotation of said annuli serving to impart a rotary motion to the work pieces within said grooves, a freely movable work retainer ring surrounding the lower annulus, said ring having an internal cylindrical work engaging surface, a revolvable inner retainer ring within said lower annulus, said latter ring having an outer cylindrical work engaging surface, and means including a positively driven crankpin supported on said base within the lower annulus which is operatively

connected to impart a revolving movement to the inner retainer ring simultaneously to impart an axial reciprocatory movement to said work pieces relative to said annuli.

5 2. In a lapping machine having a base, a vertically movable upper lapping annulus having a plane operative face thereon, a lower work supporting annulus opposed thereto having an upper plane face which is rotatably supported on said base, a plurality of radial V-shaped work supporting grooves extending across the upper plane surface of the lower annulus simultaneously to support a plurality of work pieces to be lapped, a manually operable lever pivotally supported relative to said base, means including a gear and rack operatively connecting said lever with the upper lapping annulus to facilitate moving the upper annulus toward and from the work supporting annulus to position the lapping annuli in lapping engagement with the work pieces to be lapped, a work retainer ring slidably supported relative to and surrounding said lower annulus, said ring having an internal cylindrical work engaging surface, a revolvable inner retainer within said lower annulus having an outer cylindrical work engaging surface, means including a motor on said base positively to rotate the lower work supporting annulus, means including a crankpin driven by said motor to impart a gyrating and revolving motion to said inner retainer so as to impart a simultaneous axial reciprocatory motion to said work pieces relative to said annuli, and driving connections including a rotatable shaft on said base between said motor and said crankpin.
